Stanley H. Freeman, Larchmont, N. Y.

Application April 1, 1950, Serial No. 8,922

Term of patent 14 years

(Cl. D80—5)

To all whom it may concern:

Be it known that I, Stanley H. Freeman, a citizen of the United States of America, residing at 90 Valley Road, Larchmont, county of Westchester, State of New York, have invented a new, original, and ornamental Design for a Gem Display Case, of which the following is a specification, reference being had to the accompanying drawing, forming a part hereof.

In the drawing:

Fig. 1 is a top plan view of a gem display case, showing my new design;

Fig. 2 is a top plan view with the cover removed; and

Fig. 3 is a side elevational view thereof with a portion of the cover broken away.

I claim:

The ornamental design for a gem display case, substantially as shown.

STANLEY H. FREEMAN.
